UNITED STATES PATENT OFFICE.

JOHN L. PFAU, JR., OF QUINCY, ILLINOIS.

IMPROVEMENT IN COOKING-RANGES.

Specification forming part of Letters Patent No. **139,187**, dated May 20, 1873; application filed March 17, 1873.

To all whom it may concern:

Be it known that I, J. LOUIS PFAU, Jr., of Quincy, in the county of Adams and State of Illinois, have invented a new and useful Improvement in Cooking-Ranges; and I do declare that the following is a true and accurate description thereof, reference being had to the accompanying drawing and to the letters of reference marked thereon, and being a part of this specification, in which—

Figure 1 is a longitudinal vertical section of a range having my improved fire-pot applied thereto; and Fig. 2, a vertical section of the fire-pot, enlarged.

The nature of this invention consists in the peculiar construction of a fire-pot, as more fully hereinafter set forth.

In the drawing, A represents the base-plate, A¹ the top plate, and A² the jambs or end plate, of a range having my improved fire-pot applied thereto. B is the right and B' the left hand oven, with the fire-pot C between them, resting on the base flue-plate A³. The fire-pot is either oval or circular in form, and is built up of heavy cast-iron rings, the upper edge of each having an encircling flange, c, to

receive the foot of the ring above it. The inner top edge is rabbeted to receive a lip, c', formed by rabbeting the outer edge of the lower ring above it. This rabbet is so deep that a space is left between its lip c' and the flange c of the ring it rests upon, whereby each ring is free to contract or expand under the variations of temperature independently of the others, hence avoiding the great tendency of the fire-pot to crack, if cast solid, or if in sections which are bound together. This fire-pot can be advantageously used in other forms of cooking and heating apparatus.

What I claim as my invention, and desire to secure by Letters Patent, is—

The sectional fire-pot C, each ring having an encircling flange, c, at the outer and a rabbet at the inner top edges, a space being formed between the flange and top, and a lip, c', at the lower inner edge, as and for the purpose set forth.

JOHN L. PFAU, JR.
